CLAIM

The ornamental design for a wheel axle assembly with stabilizing braces, as shown and described.

DESCRIPTION

FIG. 1 is a front, top, and right outside perspective view of a wheel axle assembly with stabilizing braces.

FIG. 2 is a right side view of a wheel axle assembly with stabilizing braces according to FIG. 1, a left side view is a mirror image of the right side view.

FIG. 3 is a back view of a wheel axle assembly with stabilizing braces according to FIG. 1, shown at an enlarged scale.

FIG. 4 is a front perspective view of a wheel axle assembly with stabilizing braces according to FIG. 1, shown at an enlarged scale.

FIG. 5 is a top view of a wheel axle assembly with stabilizing braces according to FIG. 1, shown at an enlarged scale.

FIG. 6 is a bottom view of a wheel axle assembly with stabilizing braces according to FIG. 1.

FIG. 7 is a front, bottom, and right perspective view of a wheel axle assembly with stabilizing braces according to FIG. 1; and,

FIG. 8 is a back, top, and right perspective view of a wheel axle assembly with stabilizing braces according to FIG. 1.
